UNITED STATES PATENT OFFICE

LESTER V. STOWE, OF JUNCTION CITY, CALIFORNIA

WING HEATER FOR AIRPLANES

Application filed July 30, 1928. Serial No. 296,179.

This invention relates to exhaust heaters and its general object is to provide a heating apparatus designed to prevent the accumulation of ice and snow on the wings of aircrafts and like crafts.

A further object of the invention is to provide an exhaust heater for an aircraft, that is disposed in communication with the exhaust manifold of the engine thereof and includes valve means for controlling the amount of exhaust gases passing through the heater.

Another object of the invention is to provide a heater of the character set forth, that is simple in construction, inexpensive to manufacture and install and is efficient in operation and service.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a fragmentary top plan view of an airplane showing parts broken away and illustrating the application of the heater forming the subject matter of the present invention.

Figure 2 is a sectional view taken approximately on line 2—2 of Figure 1, looking in the direction of the arrows.

Figure 3 is a sectional view illustrating the application of the valve for controlling the passage of exhaust gases to the radiator pipes for the wings.

Figure 4 is a similar view taken through the cockpit of the airplane shown and illustrating the application of the valve controlling lever.

Referring to the drawings in detail, the letter A indicates an airplane of the usual construction and which includes hollow wings B as best shown in Figure 2 of the drawings.

The letter C indicates the exhaust mani-

folds of the airplane engine and these manifolds have in communication therewith adjacent their juncture with the exhaust pipes, conduits 1 which extend rearwardly from the exhaust manifolds and are arranged in communication with vertical conduits 2 intermediate their ends, as best shown in Figure 2.

Suitably secured between the coverings of the wings B and substantially following the outline of said wings are radiator pipes 3 of substantially U-shape formation as best shown in Figure 1. These radiator pipes have their forward inner ends connected in communication with the vertical conduits at the upper and lower ends thereof, while the rear ends of the radiator pipes terminate in substantially right angle bent ends for exhausting the gases to the atmosphere.

Arranged in the rearward conduits 1 adjacent their juncture with the exhaust manifolds C is a butterfly valve 4 for controlling the passage of exhaust gases through the conduits and these butterfly valves are provided with stems 5 having secured to the outer ends thereof arms 6 for operating the valves in a manner which will be presently apparent.

The arms 6 terminate in eyes 7 which have secured therein one of the ends of coil springs 8 while the opposite ends of said springs are fixed in any appropriate manner to the fuselage of an airplane as suggested in Figure 2. The coil springs normally retain the valves 4 in closed position. Secured in the cockpit of the airplane through the medium of rivets or other like securing means is a plate 9 having formed therewith and depending therefrom a bracket which includes teeth 10 and a rearwardly extending projection 11 having an upturned end for cooperating with the bracket for supporting a lever 12 which is mounted for slidable movement through the bracket as suggested in Figure 4.

The lever 12 has one of its ends curved upon itself to provide a handle 13 while its opposite end terminates in an eye 14 for the purpose of securely receiving one of the ends of converging cables 15 while the opposite ends of said cables are secured in the eyes 7 of the arms 6.
